[57] ABSTRACT

This invention is directed to a baseball game played on a game board constructed to provide, in addition to the usual field area, a pitching and a batting area each having its own independently operable pitching or batting device. A relatively wide three-part catching receptacle is formed in the batting area and a relatively wide pitching guide channel of trough-like cross-section extends between the pitching area and the catching receptacle so that a ball impelled from the pitching area toward the catching receptacle may be caused to follow a curvilinear path toward the batting area before being "hit" or before its reception into the batting receptacle.

SIMULATED BASEBALL GAME

This invention relates to baseball game board apparatus and device improvements to simulate most of the interesting variations in pitching a ball manually to a batter.

An object of this invention is to provide improved devices and surfaces to stimulate the competitive incentive as in an actual baseball game whereby the skill of a pitcher-player is tested in controlling the various speeds and curves in pitching a ball to roll down and over a limited batting zone.

This invention also includes certain other novel features which are more fully detailed in the following specifications, claims and accompanying drawings which illustrate a preferred embodiment of this invention;

FIG. 1 is a perspective view of the simulated baseball game board.

FIG. 2 is an enlarged perspective view taken on a line 2-2 of FIG. 1 showing a bisection of the pitching surface and part of the batting apparatus.

FIG. 3 is an enlarged perspective view taken on a line 3-3 of FIG. 1 showing the projection device and a bisection of the pitching guide channel, and

FIG. 4 is an enlarged sectional view of the pitching guide channel taken on a line 4-4 of FIG. 1.

This improved baseball game board apparatus embodies a substantially square panel 5 on which suitable lines, markings and receptacles are placed to simulate a baseball field. Projecting above and enclosing the panel 5 on all four sides are beveled walls 6.

The projection element consists of a pitching handle 7 fixed on one end of the projection element shank 8 and a vertical bend at the other end to form a pitching arm 10 from which end a horizontal bend is formed forwardly and on a line with said pitching shank 8 to become the pitching end 11 which is encased with a rubber or similar pitching tip 12. The projection element is supported by a fulcrum element 36 suitably attached to the underside of the panel 5 on a line between the pitching opening 9 and the pitching guide channel 13 as shown in FIG. 3. An elongated pitching surface 15 centered lengthwise from the pitching guide channel 13 downwardly to the catcher receptacles 20 is bordered on the two long sides with an upward sloped ridge 16 and a curvature abutting the pitching guide channel 13 which is indented with a ball recess 35. At the catcher receptacles 20 end of the pitching surface 15 is an elevated plane batting zone 17 formed by a concave on each side and centered between the two batting tubes 27 as shown in FIG. 1 and bisection of FIG. 2.

The manually operated batting apparatus as shown in part in FIG. 2 consists of a batter 18 insertable into either of the batting tubes 27, a batting handle 22 fixed on one end to the batting rod 23 which is inserted through the batting opening 24 centered in the lower section of the wall 6 nearest to the catcher receptacles 20 and extending into the batting apparatus enclosure under the panel 5 where the center of a flexible wire or string 26 is fastened to the batting rod slot 25 from which one end of the string 26 is extended and coiled counterclockwise around the right batting tube 27 and linked to the tension spring 29 and the other end of said tension spring 29 is attached to the right enclosure bolt 30. The other end of the string 26 from the batting rod

slot 25 is extended and coiled clockwise around the left batting tube 27 and linked to the tension spring 29 and the other end of said tension spring 29 is attached to the left enclosure bolt 30.

5 Shallow field receptacles 31 having markings within are provided over most of the playing area on the panel 5. Also provided are catcher receptacles 20, divisional foul line elements 32, base peg holes 33 wherein base pegs 34 can be inserted, a batting element 18 and suitable balls 14. In playing the simulated baseball game, the projection element pitching tip 12 is inserted through the outfield wall opening 9 and extended under the panel 5 to the pitching guide channel 13 where the pitching arm 10 and tip 11 are inserted up, through and above the pitching guide channel 13. The pitching shank 8 is then inserted into the fulcrum element 36. A ball is placed in the ball recess 35 of the upper pitching surface 15 and the pitcher-player manipulates the 10 pitching handle 7 exteriorly of the outfield wall 6 to oscillate the pitching arm 10 and tip 12 within the pitching guide channel 13 up, down and or from side to side and push the handle 7 inwardly to cause the pitching tip 12 to strike any of the facing parts of the 15 ball 14 to roll down the pitching surface 15 as a fast or slow incuse or outcurve or fast or slow straight ball to and over the batting zone surface 17, as actuated by the 20 pitching skill and control of the pitcher-player.

25 The batter-player can bat from the left or right side of the batting zone 17 by inserting the batter 18 into the batting tube 27 and engaging the protruding side tips of the batter 18 within the batting tube slot 28 with the bat 19 in a full swing position as shown with solid lines in FIG. 2. The batter-player then pulls outwardly with the 30 handle 22 to actuate the batter 18 and bat 19 to a batting position as shown by broken lines in FIG. 2. The batter-player can then oscillate the bat 19 on a horizontal arc back and forth over the batting zone 17 to time a 35 pitched ball 14 for a swing or bunt as a batter would in an actual baseball game.

40 With the novel pitching surface 15, a pitched ball 14 can be more effectively batted only when rolling over the batting zone 17 before entering the catcher receptacles 20, therefore, a ball 14 rolling by on either side of the batting zone 17 would roll under the full swing of a bat 19 for a 'strike' and when not swung at a 'ball,' whereas a ball 14 rolling over the batting zone 17 and into the strike catcher receptacle 20 whether swung at 45 or not is called a 'strike,' consequently, the pitching and batting skills of the players will become apparent in the course of the game. As in the actual baseball game, a batted ball can become a hit, out, error etc. and subject to contingencies in most areas of the playing field, 50 therefore, to simulate most of those possible plays on a game board, field receptacles 31 having suitable lines and markings are provided on the panel 5 to indicate the scoring of a batted ball 14. Also provided are beveled walls 6 on all four sides of the panel 5 which 55 would normally prevent a batted ball 14 from going over but allow a hard hit ball 14 to go over the said beveled wall 6 for a 'home run' when occurring over fair territory between the foul line dividers 32.

60 65 I claim;

1. In a baseball game apparatus; a ball; a game board provided with a pitching area and a batting area spaced from said pitching area; a ball pitching device located

at said pitching area; a batting device located at said batting area and including a generally horizontal bat mounted for pivotal movement about a generally vertical axis; said ball pitching and batting devices being separately operable; a depressed catching receptacle formed in said game board at said batting area; and an elongated depressed pitching guide channel formed in said game board and extending between said pitching and batting areas, said guide channel being of generally trough-like cross-sectional configuration with slanted side walls and having a mean width substantially greater than that of the diameter of said ball, the pitching end of said guide channel being provided with a ball support located at an elevation above the bottom thereof and the batting end of said guide channel being provided at said catching receptacle with a centrally disposed axial ramp extending upwardly from the bottom thereof to an elevated plane and with a pair of complementary spaced parallel concave grooves disposed to either side of said ramp, the plane of rotation of said bat being sufficiently high above said concave grooves to cause said bat to pass freely over a ball passing along either thereof while being sufficiently low

to permit said bat to contact a ball rolling up said ramp onto said elevated plane.

2. The baseball game apparatus of claim 1 in which said catching receptacle is divided into three sections, 5 one of which is axially aligned with said ramp for reception of the ball rolling thereover whereby to visually demonstrate a "strike" in the event that the said bat had not contacted said ball, and the other two of which are axially aligned with said concave grooves whereby 10 to visually demonstrate a "ball" whether or not the said bat had been actuated.
3. The baseball game apparatus of claim 2 in which said pitching device includes means capable of directing the travel of said ball either along the longitudinal 15 axis of said pitching guide channel onto said ramp for an attempted "strike" or "hit" by said separately operated batting device or of directing the travel of said ball to either side wall portion of said pitching guide channel during the advance of said ball toward said 20 catching receptacle whereby to render in doubt which of said ramp or said concave grooves will receive said ball.
